FUEL SYSTEM

David Samiran, Fairfield, Ohio

Application March 13, 1939, Serial No. 261,542

21 Claims. (Cl. 158—36)

(Granted under the act of March 3, 1883, as
amended April 30, 1928; 370 O. G. 757)

The invention described herein may be manufactured and used by or for the Government for governmental purposes, without the payment to me of any royalty thereon.

The present invention relates in general to fuel systems provided with a plurality of separate fuel sources and more particularly to a fuel system in which the contents of fuel containers representative of such fuel sources are automatically connected in predetermined order to a source of fuel consumption.

It is an object of my invention to make use of fuel pressure drop in either the source selector portion or the fuel delivery portion of my fuel system, induced by successive fuel container exhaustions, to effect automatic connection of said source of fuel consumption with a succeeding full fuel container.

A further object of my invention is to disclose, individually, certain new and novel fuel systems parts through utilization of which I am able to obtain the novel automatic fuel system adjustment set forth above.

Other objects and advantages of my invention will become apparent from the following description taken in connection with the accompanying drawings, it being clearly understood that the same are by way of illustration and example only and are not to be taken as in any way limiting the spirit or scope of my invention. The spirit and scope of my invention is to be limited only by the prior art and by the terms of the appended claims.

Referring to the drawings, in which numerals of like character designate similar parts throughout the several views:

Fig. 1 is a diagrammatic representation of a first embodiment of my invention;

Fig. 2 is a similar representation of a second embodiment of my invention;

Fig. 3 shows in schematic form a third embodiment of my invention;

Fig. 4 is a mechanical representation of the central portion of Fig. 3;

Fig. 5 shows a modification in the fuel delivery portion of Fig. 2;

Fig. 6 is a cross-sectional view of one embodiment of my air-vapor eliminator and pressure responsive switch;

Fig. 7 is a cross-sectional view of a detached form of my pressure responsive switch;

Fig. 8 is a cross-sectional view of my switch pressure regulator;

Fig. 9 is a cross-sectional view of one embodiment of my fuel pressure regulator;

Fig. 11 is a cross-sectional view of a further embodiment of my air-vapor eliminator and pressure responsive switch;

Fig. 12 is a cross-sectional view of a modified form of pressure responsive switch cooperating with a venturi;

Fig. 13 is a diagrammatic plan view of a modified three circuit interrupter; and

Fig. 14 is a sectional view taken on the line 14—14 of Fig. 13.

In the first embodiment of my invention, I seek to accomplish two objectives. Firstly, I am concerned with providing means whereby a source of fuel consumption, such as an internal combustion engine fuel injector or carburetor, may be readily interconnected with any one of a plurality of fuel containers through simple manual turning of the control handle of a conventional type of selector valve. Since each of the fuel containers of Fig. 1 is provided with a remotely reading fuel gauge, and due to the further fact that the reading elements of these gauges bear a special relationship to the aforesaid control handle, it becomes but a simple matter to register a pointer provided upon the said control handle with any desired reading element, thereby assuring that a desired fuel container is operably connected with the source of fuel consumption. Secondly, I seek to provide means for automatically turning the aforesaid selector valve from a container in which all fuel has just been exhausted to the next fuel container in selector valve order from which fuel has not yet been exhausted.

The following parts are common to all three embodiments of my invention: For mere purposes of illustration, I provide three fuel containers 1, 2, and 3, respectively. Obviously, a greater or less number of containers may be provided without in any way departing from the spirit of my invention. Empty fuel container 1, as well as full fuel containers 2 and 3, are separately connected to a like number of inlets provided in a selector valve 4. A single outlet in the selector valve 4 is appropriately connected to a fuel strainer 5. An outlet in the fuel strainer 5 is commonly connected to an engine driven fuel pump 6, a manually operated wobble pump 7, and a pressure relief valve outlet in an engine carburetor noted below. Outlets in the fuel pump 6 and wobble pump 7 are commonly connected to an air-vapor eliminator 8a. In Fig. 1, I mount a pressure responsive switch 9a directly upon the

top of the air-vapor eliminator 8a. In Figs. 2 and 3, the pressure responsive switches 9b are separated from the air-vapor eliminator 8b in a manner more fully described in connection with the latter two figures. Subject to certain limitations, the pressure responsive switch 9a may also be separated from the air-vapor eliminator 8a in a manner and for a purpose more fully described in connection with the description of the second embodiment of my invention. A fuel outlet of the air-vapor eliminator 8a is connected to the inlet of an engine fuel injector 10, while an air-vapor outlet of the eliminator 8a is connected with the fuel container 3. An engine carburetor may equally well be substituted, in Fig. 1, for the fuel injector 10. A pressure regulator outlet of the injector 10 is connected to the inlet side of the fuel pump 6.

I desire to especially note, at this point, that while the fuel containers 1, 2 and 3 of Fig. 1 are illustrated as elevated with respect to the fuel pump 6, the aforesaid interpositioning may be reversed. If the fuel pump 6 is positioned above the aforesaid containers, there are height limits between pump and containers and between aircraft and ground beyond which the "vacuum type pumps" generally employed in aircraft will not function. Later reference is made to a further limitation existing in present fuel delivery systems requiring pressure control at source of consumption and how I propose to completely overcome such limitation.

In the embodiment of my invention shown in Fig. 1, the fuel containers 1 through 3 are shown to comprises a casing 11 provided with a vented filler 12 and a tank element 13 of a remotely reading fuel level gauge noted below. The tank element 13 is composed of a lever mechanism 14 supported by the body 15, a bellows 16 and a float 17. The bellows 16 is fluid filled and in the showing of Fig. 1 is at maximum expansion, due to "tank empty" condition of the fuel container 1. An outlet of each bellows 16 is operably connected with a pre-selected dial actuating element 18a, 18b, or 18c, of the above-mentioned remotely reading fuel level gauge by means of pipes 19a, 19b, and 19c. Each of the actuating elements 18a, 18b, and 18c is composed of a housing 20, a bellows 21 and a bellows rod 22 provided at its outer extremity with a gear rack 23. For the mere purpose of schematic representation, the elements 18a, 18b, and 18c, are illustrated as lying in a common plane normal to a later referred to shaft utilized to turn the selector valve 4. Like positioning of remotely reading fuel gauges 24a, 24b, and 24c, is also provided for upon a control panel 25. A shaft 26, projecting from the bottom of each of the aforesaid gauges, is operably connected with an associated gear rack 23 by means of a pinion gear 27. From the cross-sectional showing of Fig. 1, it is readily apparent that extension of the liquid filled bellows 16 causes like and simultaneous extension of the atmosphere filled bellows 21, as the whole obviously forms a liquid sealed system. Thus the pointer of the indicator dial 24a is seen to register a "tank empty" condition, while like pointers on the indicator gauges 24b and 24c show a "tank full" condition.

The selector valve 4 (as shown in Figs. 1 and 2) is composed of a housing 28 provided with three (90 degree spaced) inlets 29a, 29b, and 29c, which are separately connected with the fuel containers 1, 2, and 3 by means of pipes 30a, 30b, and 30c, respectively, and with a central

outlet 36. Its central portion is provided with a truncated conical cavity 31 adapted to receive a cork lined taper valve 32. The valve 32 is provided with a short driving shaft 33, protruding from its face of greater diameter and with an L-shaped passageway 34 having its shortest end projecting through the valve face of lesser diameter such that it is coaxially located with respect to the shaft 33 and having its long end disposed normal to the axis of the shaft 33 such that it may be successively registered with the longitudinal axes of the housing inlets 29a, 29b, and 29c. Installation of a cover plate 35 completes assembly of the selector valve 4. In order that the selector valve 4 may be remotely controlled from the panel 25, I have provided an extension shaft 37. The shaft 37 passes through the mid portion of the panel 25 and is fixedly coupled to the short driving shaft 33 by means of a sleeve 38 and driving pins 39. A control handle 40 is fixed to the opposite end of shaft 37 by means of a driving pin 41. The significance of a ratchet wheel 42a, fixed to the mid portion of the shaft 37, will be dealt with during discussion of the automatic control of the selector valve 4.

It is important that an operator of the fuel system disclosed in Fig. 1 can at all times manually adjust the selector valve 4 to any desired tank. I make this possible by positioning the three inlet ports 29a, 29b, and 29c, of the selector valve 4 and the remotely reading gauges 24a, 24b, and 24c mounted upon the panel 25 in plan coincidence, in combination with like positioning of an arrow or pointer 43 provided upon the control handle 40 and the long end of the L-shaped passageway 34 provided in the selector valve 4 in like plan coincidence. The operator need only refer to the pointer positions of his gauges 24a, 24b and 24c, in order to exactly ascertain fuel content in the fuel containers 1, 2, and 3, respectively. Observing that the container 1 is in "tank empty" condition, he thereafter has the choice of registering the arrow 43, with either the gauge 24b associated with the fuel container 2 or the gauge 24c associated with the fuel container 3, both of which indicate their respective containers as being in a "tank full" condition.

In order that automatic operation of the selector valve 4 may be more readily understood, it is essential that Fig. 6 be briefly described. It has already been stated that this figure is composed of an air-vapor eliminator 8a and a pressure responsive switch 9a mounted directly to the top thereof.

The air-vapor eliminator 8a is composed of a cup shaped housing 44 surmounted at its open end by a cover plate 45. The cover plate 45 is also adapted for separate attachment to the pressure responsive switch 9a and includes provision for pipe fitting attachment. The cup shaped housing 44 is provided at its lowermost extremity with a horizontal inlet 46, a vertical outlet 47, a drain boss 48 and a drain plug 49. The upper end of the outlet 47 is recessed to receive and fixedly hold the tube like bottom extremity of a cup shaped deflector 50. A cylindrical sieve 51, sealed to the open end of the housing 44 by means of a gasket 52 and the cover plate 45, has its lower tube like extremity adapted to be piloted into that portion of the deflector 50 which projects downwardly into the upper end of the outlet 47. The cover plate 45 is provided with an angular flange 53 adapted to receive the open end of a cup-shaped float guide 54. The bottom

of the float guide 54 is provided with a further cup-shaped guide 55 adapted to receive the lower extremity of a valve mechanism 56. The latter mechanism is composed of a tube 57 fixed to casing halves 58a and 58b of a float 59 (which may be internally reinforced, as shown, if desired), said tube having an outer collar 60 and inner collar 61 fixed to its lower extremity by means of a pin 62 and an inner collar 63 soldered or otherwise fixed to its uppermost extremity; of a needle valve 64; of a valve stem 65; and of a valve spring 66. The base of the needle valve 64 is flanged outwardly to limit upward valve movement with respect to the tube 57 by the spring 66. It will also be noted that a passageway 67 is provided through a boss 68 of the cover plate 45 and a valve seat 69 fixed therewithin. Thus, with the valve 64 in "down" position, the interior of the housing 44 is in direct communication with a vent line 70 through passageways 71, 72, 73 and 74. The vent line 70 is in turn in communication with the atmosphere through the containers 3 and vented filler 12 shown in Fig. 1.

In the pressure responsive switch 9a, a cylindrical housing 75 is separated into an upper and a lower cavity 76 and 77, by means of a common wall 78. A bearing boss 79 depends from the central portion of the wall 78. A bellows 80 is designed to seal the lower cavity 77 from fluid intercommunication with a tapped hole 81 leading directly into the interior of the housing 44 of the air-vapor eliminator 8a (i. e., when the outermost edges of the bellows are firmly clamped between a flange 82 provided upon the bottom of the housing 77, a gasket 83, and the upper outermost surface of the cover plate 45). The space between the top surface of the bellows 80 and the inner surface of the lower cavity 77 is directly vented to the atmosphere by means of a passageway 84. Two electrical binding posts 85 and 86 are fixed to the top of a dome 87 of insulating material (having a number of lightening holes drilled therethrough). Cut-outs 88 are provided in the uppermost dome surface for installation of a fixed contact 89, short coupled to the binding post 86, and a movable contact 90, long coupled to the binding post 85 by means of spring leaves 91. The mid portion of the leaves 91 is raised or lowered with reference to the base of a bellows stem 92 by vertical adjustment of a nut 93 provided upon the upper threaded end of the bellows stem 92. By means of this adjustment, spacing of the contacts 89 and 90 may be varied to any desired "gap." Prior to assembly of the above electrical parts, a washer 94 is slipped over the necked down upper portion of the bellows stem 92, a gasket 95 is placed in the bottom of the upper cavity 76, and a thin flexible diaphragm 96 is placed over the aforesaid two parts. A spring 97 and spring retaining washers 98 and 99 are next added, after which the dome assembly described above is positioned as shown in Fig. 6, and the nut 93 is screwed down to the desired adjustment. The assembly is completed by final addition of a dust cover 100.

The air-vapor eliminator 8a and the pressure responsive switch 9a described immediately above operate as follows:

Under "empty fuel" condition, the lowermost extremity of the valve mechanism 56 rests against the bottom of the cup-shaped guide 55. Under such "down condition" of the valve mechanism 56, the interior of the housing 44 is freely vented to the atmosphere through passages 67, 71, 72, 73 and 74, the vent line 70, the fuel con-

tainer 3, and the vented filler 12, as may be readily seen by joint reference to Figs. 1 and 6. With introduction of fuel through the inlet 46 provided in the base of the air-vapor eliminator 8a, raising of the fuel level within the housing 44 brings about ultimate "full up" positioning of the valve mechanism 56, whereupon the needle valve 64 seals the central aperture provided in the valve seat 69 (as shown in Fig. 6). Thereafter, additional rising of the fuel level within the housing 44 causes air trapped in the upper portion thereof, in the tapped hole 81, and in that portion of the pressure responsive switch 9a which lies intermediate of the under surface of the bellows 80 and the uppermost surface of the cover plate 45, to be ultimately expelled as noted below. Upon predetermined increase in the aforesaid pressure, repositioning of parts causes the contacts 89 and 90 to be separated in the manner shown in Fig. 6. Actual operation of my fuel system in aircraft indicates that the trapped air referred to hereinabove is gradually driven out through the vent line 70 until the combined interiors of the housing 44 and the lower cavity 77 in the housing 75 are completely liquid filled. So long as the aforesaid predetermined fuel pressure is maintained or exceeded, the contacts 89 and 90 will remain in the open position of Fig. 6. However, in the event of continued operation of the fuel system of Fig. 1 with the container 1 in the "empty" condition shown, the fuel pump 6 will no longer be able to deliver fuel to the inlet 46 and the housing 44 of the air-vapor eliminator 8a will merely act as a reserve reservoir for limited auxiliary fuel delivery to the fuel injector 10. After predetermined depletion of this auxiliary supply, the valve mechanism 56 will assume the "down position" previously referred to above. The foregoing will be simultaneously followed by "down position" of the bellows 80, resulting in closing of the contacts 89 and 90. The significance of alternate opening and closing of the aforesaid contacts is dealt with immediately below.

Having fully described the construction and operation of the air-vapor eliminator 8a and pressure responsive switch 9a, I now propose to disclose how these parts, as a unitary assembly, cooperate with a signal lamp 101, a solenoid motor 102, an impulse timer or motor control 103, a relay 104, a battery 105, an internal combustion engine ignition switch 106, an electric circuit 107 and a circuit cut-out switch 108, to effect automatic turning of the selector valve 4 from any "tank empty" condition to a "tank full" condition.

The solenoid motor 102 (shown in Fig. 1) is composed of a solenoid 109 disposed normal to the auxiliary shaft 37 and lying in a common plane with the ratchet wheel 42a, a mounting panel 110 provided with a positive terminal 111 and a hinged dog 112 consisting of connecting links 113 and driving pins 114. Due to hinged attachment of the rear end of the dog 112 to the solenoid 109, the ratchet wheel 42a may be freely manually adjusted by the control handle 40 in a clockwise direction. Following each outward stroke or impulse of the solenoid 109, the forward end of the dog 112 is drawn upwardly and backwardly to a point where it automatically "falls down" into engagement with the "next-to-be-engaged tooth" of the ratchet wheel 42a. While Fig. 1 shows provision for clockwise manual adjustment of the selector valve 4 only, it is to be understood that the ratchet wheel 42a may

be provided with an appropriate mechanism permitting manual adjustment of the selector valve 4 in a counter-clockwise direction as well as the present clockwise direction.

The motor control 103 is composed of a motor element 115 and a make-and-break element 116. For simplicity's sake, the motor element 115 is diagrammatically represented by conventional commutator, brushes, coil and ground, with "positive lead" connected to a terminal 117. The motor element 115 is geared to a ratchet wheel 118 (of the make-and-break element 116) such that the latter is turned at a greatly reduced "rate" with respect to the former. In the showing of Fig. 1, the ratchet wheel 118 is only provided with a single "tooth" such that each clockwise revolution thereof will produce a single "closing" of the make-and-break element 116. The time interval between any two successive "closings" of the element 116 must be greater than the elapsed time required for the selector valve to leave an empty fuel container, to connect with a full fuel container and for the fuel pump to thereafter build up sufficient pressure to effect opening of the pressure responsive switch 9a. In the second embodiment of my invention, I propose alternative utilization of the motor control 103 (in lieu of a later referred to circuit cut-out switch). The latter usage should be accompanied by an increase in the number of "teeth" provided upon the ratchet wheel 118 or the turning rate of the wheel 118 should be increased for reasons fully discussed herein below. One "lead" of the make-and-break element 116 is commonly connected to the "positive lead" of the motor element 115 and the terminal 117 (of the motor control 103), while the other "lead" thereof is connected to the remaining terminal 119 of the motor control 103.

The relay 104 is provided with make-and-break terminals 120 and 121, and with a positive coil terminal 122. Terminal 120 is connected to the terminal 111 of the solenoid motor 102. Opposite terminal 121 is commonly connected to the binding post 86 of the pressure responsive switch 9a (see Fig. 6), to a positive terminal 123 provided upon a small control panel 133a, to the positive pole of the battery 105 and to the positive "testing" terminal 124 of the signal lamp 101. Positive (relay) terminal 122 is connected to the terminal 119 of the motor control 103. The other terminal 117, of the motor control 103, is commonly connected to a second terminal 125 provided upon the control panel 133a (through the circuit cut-out switch 108), to a positive "operating" terminal 126 of the signal lamp 101, and to the binding post 85 of the pressure responsive switch 9a (see Fig. 6). The aggregate of the above described connections may be taken as constituting the electric circuit 107 referred to at the commencement of the second preceding paragraph above.

Functioning of the electrical circuit 107 can be most readily understood when described in correlation with the following operating steps observed in connection with the fuel system shown in Fig. 1. For "off-engine" condition, no fuel is flowing, the ignition switch 106 is "off," and the electrical circuit 107 is inoperative. On the other hand, for "on-engine" condition, it must be assumed that fuel is flowing, that pressure incident thereto maintains contacts 89 and 90 in the "open" condition of Fig. 6, and that the ignition switch 106 is "on";

resulting in an electric current being delivered to terminals 123 (panel), 124 (lamp), 121 (relay), and to the binding post 86 (pressure responsive switch). Thereafter, the operator presses down upon a push button 127 of the signal lamp 101 to make certain that the light portion thereof is properly functioning. If the latter be true, he then closes the cut-out switch 108 of the electrical circuit 107, which is the last manual operation necessary to assure automatic adjustment of the selector valve 4.

"On-engine" functioning of the electrical circuit 107 is divided into the sub-operating steps of "closed contact" condition of the pressure responsive switch 9a, in effect so long as the fuel pump remains continuously connected with an empty fuel container (as would be the case in Fig. 1), and "open contact" condition of the pressure responsive switch 9a shown in Fig. 6, which latter condition is in effect so long as an uninterrupted supply of fuel is delivered to the fuel pump 6 by the selector valve 4.

Let us first trace sub-circuit operation under "closed contact" condition. Obviously, thereunder, the selector valve 4 must be turned to a "tank full" condition (either by means of the control handle 40 or the solenoid motor 102) if the engine connected with the carburetor 16 is to continue to function. Regardless of which of the aforesaid "means" is employed, it is further important that an operator of the fuel system of Fig. 1 receive immediate visual warning of the above condition. The latter is simply and automatically accomplished. With closing of the contacts 89 and 90 of the pressure responsive switch 9a, electric current from the battery 105 passes directly through the light portion of the signal lamp 101 to the ground, via the binding posts 85 and 86 and the terminals 125, 126 and 128. I wish to call attention, at this point, to the fact that in so far as the control panel 133a is concerned, closing of the above contacts 89 and 90 immediately effects direct connection of panel terminal 125 with the positive pole of the battery 105.

The second sub-circuit, under the above "closed contacts" condition, concerns primarily the motor control 103 and secondarily the solenoid motor 102 which it controls. So long as the pressure responsive switch 9a remains closed, electric current will continue to pass from the terminal 125 of the control panel 133a to the ground of the control motor 102 (through the cut-out switch 108, the terminal 117 and the motor element 115), resulting in continuous slow counter-clockwise turning of the ratchet wheel 118. Since the single "tooth" of the latter wheel initially starts from a position closely approximating the showing of Fig. 1, a relatively short period only is required to effect closing of the make-and-break element 116. Thereafter two things occur, one very brief in its duration and the other much longer in duration.

Firstly, closing of the make-and-break element 116 produces an immediate closed circuit across terminals 117 and 119 of the motor control 103. Current from the terminal 125 of the panel 133a thereafter passes directly to the ground of the relay 104 (through the cut-out switch 108 and the terminals 117, 119 and 122), closing the breaker portion 130 of the relay 104. Closing of the relay 104 effects secondary current flow from terminal 125 of the panel 133a to the ground of the solenoid 109 (through binding posts 85 and 86 of the pressure responsive

switch 9a, the terminals 121 and 120 of the relay 104 and the positive terminal 111). The latter current flow causes the hinged dog 112 to execute a single forward impulse resulting in a one-quarter counterclockwise revolution of the ratchet wheel 42a. The dog 112 remains in extended position until the "tooth" of the ratchet wheel 118 has turned sufficiently to open the make-and-break element 116. Thereafter, the forward end of the dog 112 is drawn upwardly and backwardly into a position from which it falls downwardly into operable engagement with the next oncoming "tooth" of the ratchet wheel 42a. Secondly, the motor element 118 continues to turn until the fuel pump 6 builds up sufficient pressure to effect opening of the pressure responsive switch 9a, at which time the "tooth" of the ratchet wheel 118 has rotated into a position closely approximating the showing of Fig. 1. Should, for any reason whatsoever, the automatic adjustment hereinabove described fail to function, the operator of the fuel system of Fig. 1 has but to open the circuit cut-out switch 108 to be thereafter completely free to accomplish any manual adjustment of the selector valve 4 he may desire under guidance of the pointer readings of gauges 24a, 24b and 24c.

In the second embodiment of my invention, (shown in Fig. 2) I continue to seek accomplishment of the two objects enumerated in connection with the first embodiment thereof. Through slight modification of the "ratchet scheme" of Fig. 1, I am able to accomplish manual adjustment of the selector valve 4 in both clockwise and counter-clockwise directions. In the means for accomplishing automatic turning of the aforesaid selector valve, I provide a mechanism which assures more exact registration of the selector valve 4 upon connection with any container in which fuel still remains unexhausted.

Fig. 2 has been materially simplified by omission therefrom of the triple showings of fuel containers (1 through 3), tank elements (13), dial actuating elements (18) and remotely reading fuel gauges (24) formerly incorporated in Fig. 1. To further clarify wiring details, only a limited central portion of the control panel 25 is shown in full outline, the outer edges thereof being shown in phantom. It should be clearly understood that the aforesaid omission of fuel gauge parts is not intended to convey the impression that these parts should necessarily be omitted from an actual aircraft installation representative of Fig. 2.

I now refer to certain new part substitutions accomplished in Fig. 2. It should be noted that in the place of the impulse timer or motor control 103 of Fig. 1 I substitute a circuit cut-out switch 131, that in lieu of the "single wire" electric circuit 107 of the same figure I substitute a "double wire" electric circuit 132, that in lieu of the "two terminal" control panel 133a I substitute a "three terminal" control panel 133b (having a new terminal 134 replacing the four "ground showings" of Fig. 1) and that in lieu of the "combined" air-vapor eliminator 8a and pressure responsive switch 9a I substitute "separated" air-vapor eliminator 8b (i. e., the eliminator 8a with a plug 135 inserted in the tapped hole 81 in the cover plate 45) and pressure responsive switch 9b.

I have previously stated in connection with the first embodiment of my invention, that, subject to certain limitations, the pressure responsive switch 9a (of Fig. 1) can be directly connected

to the outlet of the fuel pump 6 through suitable pipe connection with the tapped hole 81 provided in the cover plate 45. The above limitations are two-fold. Firstly, the fuel system must incorporate an engine carburetor or an engine fuel injector (if the latter possesses its own air-vapor eliminator) that is directly connected to the outlet of its fuel pump; i. e., there is no air-vapor eliminator present. Secondly, the outlets of the fuel containers of the system must be provided with short stand pipe extensions having a predetermined opening at the base of each. The latter provides a sufficient partial pressure drop to effect "closed circuiting" of the system's pressure responsive switch (as in Fig. 1) and at the same time assures a predetermined reserve fuel supply during the period in which the system's selector valve is moving from "tank empty" to "tank full" condition.

Returning to the part showings of Fig. 2, since the pressure responsive switch 9b is no longer directly pressure connected to the air-vapor eliminator, I provide independent pipe connection between one bellows element of the pressure responsive switch 9b and the outlet of the fuel pump 6, the said connection forming part of a switch pressure regulator 136, the construction details of which are fully disclosed in Fig. 8. I also provide pipe connection between a second bellows element of the pressure responsive switch 9b and the induction system of an aircraft supercharged engine. Fig. 7 discloses the construction details of the new pressure responsive switch 9b. The latter is brought into operable connection with the extension shaft 37 of the selector valve 4 by means of a control disk 137 (fixed to shaft 37) provided with tripping cams 138a, 138b, and 138c.

I have previously called attention to the possible desirability of substituting the motor control 103 (of Fig. 1) in lieu of the circuit cut-out switch 131 shown in the second embodiment of my invention. In such an event, the rate of turning of the ratchet wheel 118 should be markedly increased (over that suitable for the first embodiment of my invention) or the single "tooth" shown in Fig. 1 should be supplemented by a plurality of such "teeth." The necessity for incorporating one or the other of these two changes will become more apparent as the description of Fig. 2 progresses. It is sufficient to note, at this point, that in the second embodiment of my invention inter-action of the control disk 137 with the pressure responsive switch 9b effects proper stoppage of the selector valve 4 upon registry with the next fuel container in "tank full" condition. In Fig. 1, each recurring impulse of the solenoid 102 registers the selector valve 4 with a new fuel container, regardless of whether the latter be in "tank full" or "tank empty" condition.

In order that the second embodiment of my automatic operation of the selector valve 4 may be more readily understood, it is essential that Figs. 7 and 8 be briefly described. The pressure responsive switch 9b (shown in Fig. 7) is composed of many parts variously disposed in and about a cylindrical housing 139 separated into an upper and a lower cavity 140 and 141, by means of a common wall 142. An upper bellows element 143 is fixed within the upper cavity 140 by means of a gasket 144 and a holdown plate 145. A lower bellows element 146 is fixed in continuation of the lower cavity 141 by means of a gasket 147 and a holdown ring 148 provided with a dust cover

149. The free ends of bellows elements 143 and 146 are utilized to effect longitudinal displacement of a switch carriage 150, composed of an upper carriage element 151, a lower carriage element 152, two spacer rods 153, nuts 154 and lock washers 155. The spacer rods 153 are guided in their longitudinal movement by two associated and coaxially disposed holes provided in parts 143 through 148, respectively.

150. The upper bellows element 143 is composed of an annular top plate 156, a bellows 157 soldered to the inner edge thereto, a cup-shaped bottom plate 158 with outer edge soldered to the bellows 157 and an upstanding shaft 159 fixed to the central portion of the bottom plate 158. The shaft 159 is guided in the holdown plate 145 by means of a bushing 160. The holdown plate 145 is further suitably tapped for introduction of an upwardly projecting stud 161, provided with an adjusting hole 162 and a check nut 163. Prior installation of the latter part, a circular sheet 164 of insulating material is placed upon the top of the holdown plate 145 and a vertical vent hole 165 is drilled through both parts.

151. The lower bellows element 146 is composed of an annular top plate 166, a bellows 167 soldered thereto, and a bottom plate 168 likewise soldered to the bellows 167. The bottom plate 168 is provided with a central opening 169 surrounded by an upstanding cylindrical portion 170 having oppositely disposed slots 171 closed at their open ends by a snap ring 172.

152. The lower carriage element 152 is composed of a cross-bar 173 having a central opening 174, a holdown spring 175, and a spring loading or compression adjustor 176. The adjustor 176 comprises a centrally flanged stud 177 with both ends threaded, a spring seat 178 with lateral projections 179 adapted to slide longitudinally in the slots 171 (of bottom plate 168), a gasket 180, a lockwasher 181 and a check nut 182. Upon appropriate "loosening" of the check nut 182, adjustment is readily accomplished by means of a screw driver slot 183 placed in the bottom of the flanged stud 177. Turning of the aforesaid stud causes the spring seat 178 to be raised from the "bottom position" showing of Fig. 7 to a "top position" in which further upward movement is prevented through contact of the projections 179 against the snap ring 172. This adjustment assures a wide range of varying spring compressions tending to maintain the switch carriage 150 in the "down" or what is later herein referred to as the "P" switch positionings of Figs. 2 and 7.

153. The upper carriage element 151 is composed of a cross-bar 183 having a central opening 184 relative to which the upper extremity of the upstanding shaft 159 may freely slide and a pair of journal bosses 185, a contactor arm element 186, and metallic contact plates 187 and 188 supported on insulation blocks 189 and 190, the whole being fixed to the top surface of the cross-bar 183 by means of screws 191, a plain washer 192 and a lock washer 193. The contactor arm element 186 consists of a hollow bar 194 journaled to the bosses 185 by means of a pin 195 and having a cam 196 upon the upper outer surface thereof, a compression spring 197, a support 198 (composed of insulation material), a metallic roller 199 and a pin 200 for securing the roller 199 to its support 198. It should be noted that the apex of the V-shaped portion of the contact plate 188 is slightly more remotely located from the top surface of the cross-bar 183 than is the longitudinal axis of the

pin 195 about which the contactor arm element 186 pivots.

154. Before proceeding with a description of Fig. 8, I desire to note that that portion of the upper cavity 140 (of the pressure responsive switch 9b) lying immediately exterior of the outside surface of the upper bellows element 143 is adapted to be directly fluid connected with the switch pressure regulator 136 (as shown in Fig. 2), the interior of the upper bellows element 143 being atmosphere vented through the vertical vent hole 165 drilled in the holdown plate 145 and the circular sheet 164 of insulating material. I further desire to note that that portion of the lower cavity 141 lying exterior of the inside surface of the lower bellows element 146 is adapted to be directly fluid connected with the induction system of a supercharged aircraft engine in a manner and for a purpose later referred to herein, the exterior of the lower bellows element 146 being atmosphere vented through a horizontal vent hole 201 provided in the dust cover 149. In the event that the second embodiment of my invention is employed in conjunction with an aircraft equipped with an unsupercharged engine, or an engine in which the supercharger does not effect the fuel injector or carburetor, the interior of the lower bellows element 146 is directly vented to the atmosphere.

155. The switch pressure regulator 136 (shown in Figs. 2, 5 and 8) is composed of a housing 202, with an inlet 203, an outlet 204 leading into and out of a pressure regulator element cavity 205 and a by-pass 206 leading directly out of the inlet 203, and of a pressure regulator element 208 disposed within and sealing the aforesaid cavity 205. A baffle element 207 is operably connected to the by-pass 206. It consists of a housing 209, a gasket 210, five "staggered" baffle plates 211 and attaching screws 212. The element 207 prevents undesired fluid escapage from the pressure responsive switch 9b. It should be noted (by cross-reference to Fig. 2) that the inlet 203 is operably connected to the outlet of the fuel pump 6, that the outlet 204 is operably connected to the inlet 46 of the air-vapor eliminator 8b, and that the baffle element 207 (forming a continuation of the by-pass 206) is operably connected to the upper cavity 140 of the pressure responsive switch 9b. Conventional means is provided for eliminating initial air trapped within the upper cavity 140, upon initial flow of fluid from the pressure regulator 136 to the upper cavity 140 of the pressure responsive switch 9b.

156. Prior to entry into a description of the pressure regulator element 208, I desire to note that the design of its spring loading or compression adjustment is identical to that of the compression adjustor 176 of the pressure responsive switch 9b (shown in Fig. 7). The element 208 (consisting of an entirely self contained and therefore readily removable sub-assembly) is composed of a body portion 213 provided with a top plate 214 having a central opening 215 surrounded by a depending cylindrical portion 216 with oppositely disposed slots 217 closed at their open ends by a snap ring 218, a conical valve 219 with a "by-pass" passageway 220 through the seat portion thereof, a holdown spring 221, and a compression adjustor 222. The adjustor 222 comprises a centrally flanged stud 223 with both ends threaded (one of which has a vented cavity for guidance of the stem portion of the conical valve 219), the spring seat 178, the gasket 180, a new gasket 224, lock wires 225 and 226, and a check nut 227. The screw driver slot 183 placed in the

top of the flanged stud permits adjustment thereof in a manner identical to adjustment of the adjustor 176 of the pressure responsive switch 9b (shown in Fig. 7).

The switch pressure regulator 136 operates as follows: During active operation (i. e., during all turnings) of the fuel pump 6, fuel entering the inlet 203 is accomplishing two results. Firstly, it is inducing one or the other of two ranges of pressure upon the upper cavity 140 of the pressure responsive switch 9b. If the rate of discharge through the by-passes 220 provided in the conical valve 219 is low, a "low pressure" reaction insufficient to materially compress the hold-down spring 175 (of switch 9b) results. On the other hand, if the rate of discharge through the aforesaid by-passes 220 is high, a "high pressure" reaction sufficient to fully compress the hold-down spring 175 (of switch 9b) results. Under full engine revolution, approximately one second only is required to effect the last named result upon fuel entry in the rotor portion of the pump 6. Secondly, fuel entering the inlet 203 is inducing continuous secondary flow of fuel from the outlet 204 to the air-vapor eliminator 8b and from thence to the engine carburetor 10 operably connected therewith. The pressure magnitude of this secondary flow of fuel (in so far as the switch pressure regulator 136 is concerned) is controlled by means of the regulator element 208. Should momentary fuel pressure in the inlet 203 "build up" in excess of desired pressure, the head portion of the conical valve 219 moves off its associated seat, thus increasing flow of fuel through the outlet 204 of the switch pressure regulator 136. The fuel injector 10 includes (as an integral part of its own structure) a pressure relief valve 228 whereby fuel pressure in excess of a predetermined value, occurring exteriorly of the outlet 204 of the switch pressure regulator 136, is automatically by-passed to the inlet side of the fuel pump 6.

The two phased operation of the pressure responsive switch 9b (shown in Figs. 2 and 7) is as follows: By way of illustration, only, let it be assumed that the compression adjustor 222 is first adjusted such that a steady flow of fuel under five pound pressure is delivered by the by-pass 208 of the switch pressure regulator 136. Under such condition, a like five pound fuel pressure is present in the upper cavity 140, of the pressure responsive switch 9b. Therefore, a second adjustment of the compression adjustor 176 of the latter switch must be made such that the spring 175 thereof will be sufficiently compressed to permit upward movement of the switch carriage 150 into a position disposing the contactor arm cam 196 coincident with the dotted "+P" outline shown at the top of Fig. 7. The significance of the latter "+P" cam positioning is later discussed below.

The second phase of operation of the pressure regulator switch 9b (shown in Figs. 2 and 7) is concerned with application of the second embodiment of my invention (shown in Fig. 2) to an aircraft equipped with an engine in which the supercharger controls the air inlet pressure of its fuel injector or carburetor. In such an installation, as the aircraft continues to gain altitude, the pressure required to deliver fuel to its engine injector or carburetor steadily increases in magnitude. It naturally follows that the aforesaid increase in fuel pressure is directly transmitted to the upper cavity 140 (of the switch 9b).

Should only the spring 175 resist the aforesaid increased pressure, premature upward movement of the switch carriage 150 would result. To prevent such premature movement, that portion of the lower cavity 141 lying exterior of the inside surface of the lower bellows element 146 is directly fluid connected with the induction system of the aforesaid supercharged engine. This effects complete compensation for the above fuel pressure increase, the detailed character of which is fully explained hereinbelow (in connection with the description of Fig. 5).

Having fully described the construction and operation of the pressure responsive switch 9b and the switch pressure regulator 136, I now propose to disclose how these parts cooperate with the control disk 137, circuit cut-out switches 108 and 131 and electric circuit 132 (of Fig. 2) and with the signal lamp 101, solenoid motor 102, relay 104, battery 105 and ignition switch 106 (of Figs. 1 and 2), to effect automatic turning of the selector valve 4 from any "tank empty" condition to a "tank full" condition. In lieu of the motor control 103 employed in the first embodiment of my invention, I substitute the circuit cut-out switch 131, the operating arm of which is operably connected to a hinged dog 229. The engaging tip of the dog 229 is held in initial horizontal attitude by means of a spring 230. Upon energization of the solenoid motor 102, the forward end of the dog 229 moves outwardly and slightly upwardly, which movement simultaneously carries the operating arm of the switch 131 into an "off" position. The circumstances under which the solenoid motor 102 is so energized are dealt with below.

In the "double wire" electric circuit 132, interconnection of the battery 105 with the signal lamp 101, the relay 104 and the ignition switch 106 is fundamentally the same as interconnection of like parts in the "single wire" electric circuit 107 of Fig. 1. The Fig. 1 direct connection between positive terminal 111 (solenoid motor) and terminal 120 (relay), is in Fig. 2 carried through the two circuit cut-out switches 108 and 131. Both terminals of the coil portion 129 (relay) of Fig. 2 are connected in series with terminals 126 and 128 of the signal switch 101. Any current in the former, therefore, lights the latter.

Functioning of the electrical circuit 132 is as follows: For "off-engine" condition, as was the case in Fig. 1, the entire circuit is inoperative. For "on-engine" condition, it must be assumed that fuel is flowing, that the roller 199 is between the base of the insulation block 190 and the plate 188 of the pressure responsive switch 9b (i. e., not between plates 187 and 180, due to part interactions explained below), that pressure incident to normal fuel flow has moved the switch carriage 150 into the "+P" dotted position shown in Fig. 7, and that the ignition switch 106 is "on". Under the above stated conditions, electric current from the "plus" pole of the battery 105 is delivered to terminals 123 (panel), 124 (lamp), 121 (relay) and to the plate 188 (pressure responsive switch). Before such current can return to the "minus" pole of the battery 105, from the remaining terminals 126 and 128 of the signal lamp 101 or the terminal 121 of the relay 104, certain parts illustrated in Fig. 2 must undergo physical displacement. In the case of the signal lamp 101, either the push button 127 utilized to test working condition of the light element installed therewithin must be pushed down (thereby connecting terminal 128 with negative ter-

terminal 134 of the panel 133b) or the metallic roller 199 of the pressure responsive switch 9b must assume a position between the metallic contact plates 187 and 188 as shown in Fig. 7 (thereby firstly directly inter-connecting terminals 123 and 125 of the panel 133b, and, as a result of such common inter-connection, secondly continuously connecting the "plus" pole of the battery 105 with terminal 126 of the signal lamp 101, resulting in continuous illumination of the same due to common inter-connection between additional terminal 128 thereof and the negative terminal 134 of the panel 133b). In the case of the relay 104, whenever the signal lamp 101 is illuminated, due to "closing" of the pressure responsive switch 9b (as discussed above), current is also continuously flowing from the "plus" pole of the battery 105 directly through the coil portion 129 of the relay 104 and from the negative terminal 134 of the panel 133b directly back to the "minus" pole of the battery 105. The part played by coincident closing of the contact portion of the relay 104 can now be explained.

Let it be assumed, in Fig. 2, that switches 106 and 108 are in an "on" position and that the fuel pump 6 has not only exhausted the container 1, but that sufficient time has elapsed to effect simultaneous pressure drop in both the by-pass portion of the switch pressure regulator 136 and the cavity 140 of the pressure responsive switch 9b, resulting in upward movement of the switch carriage 150 into the "—P" position indicated in Fig. 2. The aforesaid upward carriage movement effects automatic "closing" of both the pressure responsive switch 9a and the relay 104, resulting in current from the positive terminal 123 of the panel 133b passing directly through the solenoid motor 102 and back to the negative terminal 134 of the panel 133b (through the terminals 121 and 120, the switches 108 and 131, and the negative terminal of the solenoid motor 102). Impulses from the solenoid 102 thereupon effect simultaneous turning of the ratchet wheel 42b and the valve 32 until the long end of the L-shaped passageway 34 of the latter passes into registration with inlet 29b of the housing 28. As a result of the above registration, fuel from the newly connected container 2 immediately commences to flow into the fuel pump 6, from whence it passes directly into the switch pressure regulator 136. It should be noted, at this point, that the tripping cam 138b now approximately occupies the present (Fig. 2) indicated position of the tripping cam 138a. With lifting of the conical valve 219 off the seat provided in the housing 202, pressure transmitted by the by-pass 206 to the cavity 140 of the pressure responsive switch 9b causes the switch carriage 150 to move into the dotted "+P" position indicated in Fig. 2. This latter carriage movement effects contact between the above mentioned tripping cam 138b and the cam 196 provided upon the hollow bar 194, causing the metallic roller 199 to be dislodged from its position between the metallic plates 187 and 188. As the metallic roller 199 assumes a new position intermediate of the metallic contact plate 188 and the base of the insulation block 190, interconnection between terminals 123 and 125 of the panel 133b ceases and the contact portion of the relay 104 immediately opens, terminating flow of electric current to the solenoid motor 102.

The aforesaid parts continue to remain in the last named attitude until exhaustion of fuel from

the container 2 causes complete repetition of the operating cycle set forth above.

In the third embodiment of my invention, I not only accomplish the two objectives enumerated in connection with the first and second embodiments thereof in an improved manner, but, in addition, I accomplish a third object discussed in detail below. In place of the solenoid motor-ratchet "drives" illustrated in Figs. 1 and 2, my third embodiment employs a unitary selector valve drive for accomplishing turning of the extension shaft 37, and thereby, actuation of my selector valve 4. By the further addition of a solenoid energized clutch, I am also able to accomplish full manual adjustment of the selector valve 4 in both clockwise and counter-clockwise directions at all times. In the means for accomplishing automatic turning of the aforesaid selector valve, I provide a mechanism capable of accomplishing very exact registration of the selector valve 4 upon connection with any container in which fuel still remains unexhausted. In addition, where registration with an empty tank is encountered, I provide additional means for uniformly continuing valve rotation until such time as registration is accomplished with a still unexhausted container.

In connection with the last named improvement, I substitute for the hydrostatic fuel level gauges illustrated in Figs. 1 and 2, electrical fuel level gauges of the remote reading type shown in Fig. 3. I am able to accomplish the continuous valve turning feature noted above through incorporation, in the tank elements of my electric fuel gauges, of a special contactor the detailed nature of which is fully discussed below.

In the schematic showing of Fig. 3, I have illustrated only such parts commonly used in the second and third embodiments of my invention as are essential to an understanding of the character and functioning of my new selector valve drive and substitute electrical remotely reading fuel level gauges. I have previously stated, at the commencement of this specification, that those parts which bear the numerical designation "1" through "10" are common to all three embodiments of my invention. At the top and mid-portions of Fig. 3 there are represented in diagrammatic form, respectively, tank elements 231a, 231b and 231c, and panel elements 232a, 232b and 232c, of three remotely reading fuel level gauges supported, respectively, by the fuel containers 1, 2 and 3 (i. e., parts 231a through 231c) and the panel 25 (i. e., parts 232a through 232c).

Since it is assumed, in Fig. 3, that the fuel container 1 is in "tank empty" condition and that the fuel containers 2 and 3 are in "tank full" condition (as is also the case in Figs. 1 and 2); a contactor arm 233 of the tank element 231a is seen in maximum counter-clockwise position with respect to a rheostat 234 provided with "plus" terminal 235 and "minus" terminal 236. The counter-clockwise side of the contactor arm 233 is provided with a bumper block 237 (of insulating material) for closing the "points" of a breaker 238. One end of both the rheostat 234 and the breaker 238 is served by the common terminal 235. The other end of the breaker 238 is provided with a "plus" terminal 239. It will be noted that the terminal 236 of the rheostat 234 is directly grounded.

The panel elements 232a, 232b and 232c are each provided with a grounded terminal 240, a "plus" terminal 241 (all of which are commonly connected to the "plus" pole of the battery 105

through a "gauge" circuit cut-out switch 242, a fuse 243 and a resistance 244, a second "plus" terminal 245 (each of which is separately connected to a terminal 235 of a tank element 231), and a terminal 246, (each of which is connected to the pivoted end of a separate contactor arm 233 of a tank element 231). In combination with a leg-end "off," the above panel elements are symmetrically spaced about the extension shaft 37 at 90 degree intervals (the legend "off" lowermost). The prior relationship, in Fig. 1, between the arrow 43 provided upon the control handle 40 and the long end of the L-shaped passageway 34 provided in the selector valve 4, between the remotely reading gauges (represented in Fig. 3 by parts "232a," "232b" and "232c") and the three inlet ports 29a, 29b and 29c of the selector valve 4, and between the last named inlet ports and the fuel containers 1, 2 and 3, is retained in Fig. 3. While showing of the ignition switch 106 upon the panel 25 is retained; for diagrammatic reasons, showing of the circuit cut-out switch 108 is shifted to the bottom of Fig. 3. While the latter switch implies manual operation, it is of course to be understood that the same can be automatically operated by fluid pressure or electric current created by starting of the engine.

In the third embodiment of my invention, I substitute a unitary selector valve drive 247 (shown in Figs. 3 and 4) in lieu of the ratchet wheel 42b, the solenoid motor 102, the circuit cut-out switch 131 and the hinged dog 229 of the second embodiment of my invention (shown in Fig. 2). The drive 247 is composed of a motor element 248, a clutch element 249, and a shaft element 250, the latter two of which are encased within a housing 251. The motor element 248 consists of a small direct current motor 252 having a geared-down drive shaft 253 to the open end of which is fixed a driving bevel gear 254.

The clutch element 249 consists of a solenoid 255 fixed to the housing 251 and an engaging portion 256 rotatably supported by a journal boss 257 forming an integral part of the housing 251. The latter engaging portion consists of a centrally flanged sleeve 258 with square hollow interior slidably engaged by a clutch member 259, a sleeve cap 260 performing the dual objects of a retainer for a compression spring 261 (constantly forcing the clutch member 259 upwardly against the plunger rod of the solenoid 255) and of a bushing rotatable within the journal boss 257. To the upper exterior end of the centrally flanged sleeve 258 is fixed a driven bevel gear 262 held at all times in operable mesh with the driving bevel gear 254. There is jointly journaled to the driven bevel gear 262 and the centrally flanged sleeve 258 a disk 263 (of insulating material) provided with tripping cams 264 (shown in Fig. 3). Relative rotational movement of the disk 263 with respect to a later referred to driven bevel gear (fixed to the centrally flanged sleeve 258) is controlled by a coil spring 265, a diagrammatic side elevation of which is shown in Fig. 3. There is finally journaled to the uppermost exterior of the centrally flanged sleeve 258 the combination clutch member-idler gear 266 referred to in the above sentence.

The member-gear 266 normally remains stationary during those periods in which the centrally flanged sleeve 258 is being rotated by the motor element 248. However, if during such rotation, the solenoid 255 is energized, an annular serrated under surface 267 of the clutch member 259 is forced downwardly into driving en-

gagement with an annular serrated over-surface 288 of the combination clutch member-idler gear 266 by a plunger rod 269 of the solenoid 255, resulting in like rotational movement of both the driven bevel gear 262 and the member-gear 266. Since the last named part is in operable engagement with the shaft element 250, secondary rotational movement of the latter element will also be accomplished.

The shaft element 250 of the unitary selector valve drive 247 is composed of a driven portion 270 and a switch portion 271. The driven portion 270 consists of a driven gear 272 and a disk 273 (of insulating material) provided with tripping cams 274a, 274b and 274c. The driven gear 272 and the disk 273 may be fixed to a driving flange 275 provided on the extension shaft 37 in any suitable manner. The extension shaft 37 is supported in the housing 251 by means of a lower bearing 276 and a split upper bearing 277. The latter bearing is fixed with respect to the housing 251 by means of a split cover plate 278 having adjustment openings 279 normally sealed by a dust cover 280 secured to the plate 278 by means of a retaining ring 281.

Referring to both Figs. 3 and 4, it is seen that the switch 271 of the shaft element 250 is composed of a three circuit interruptor 282 and a single circuit breaker 283. The interruptor 282 consists of a cylinder 284 (of insulating material) fixed to the extension shaft 37 and having three commutator segments 285a, 285b and 285c, symmetrically disposed (in end elevation), respectively, with associated tripping cams 138a, 138b and 138c provided upon the control disk 137 (common to Figs. 1, 2, 3 and 4); of three separate brushes 286a, 286b and 286c; and of a three fingered single terminal brush 287. The latter brush is directly connected to the make-and-break terminal 121 of the relay 104, while the former three brushes are directly connected, respectively, to a terminal 239 of the tank elements 231a, 231b and 231c. Since the remaining (make-and-break) terminal 120 of the relay 104 is directly connected to a "plus" terminal 288 of the solenoid 255, it is at once evident that successive closings of the breaker 238 of "231a," the breaker 238 of "231b" and the breaker 238 of "231c" (due to "tank empty" condition), in combination with like successive closings of parts "286a—285a—287" and the make-and-break portion of the relay 104, of parts "286b—285b—287" and the make-and-break portion of the relay 104, and of parts "286c—285c—287" and the make-and-break portion of the relay 104 will cause energization of the clutch solenoid 255. So long as the aforesaid energization continues, any turning of the driving bevel gear 254 of the motor 252 will induce counter-clockwise turning of the extension shaft 37 as viewed in Fig. 3.

The single circuit breaker 283 (best shown in Fig. 3) is composed of a pivoted contact arm 289 (of insulating material) partially cut away upon one side to permit free counter-clockwise movement of a leaf spring 290 affixed thereto and having a cam 291 fixed to its mid right hand portion and a contact point 292 fixed to its top left hand portion, the open end of said arm being bent slightly to the left and terminating in a cam 293 oppositely and outwardly disposed with respect to the spring cam 291. The breaker 283 is completed by addition of a tension spring 294, utilized to maintain the cam 293 in continuous contact with the disk 273. A contact point 295 is operably associated with the contact

292 provided upon the top left hand portion of the leaf spring 290.

The lower half of the diagrammatic showing of Fig. 3 is completed by incorporation of a signal lamp 296 having its "plus" terminal 297 directly connected to the metallic contact plate 188 of the pressure responsive switch 9b and by the further addition of a variable resistance 298 having a terminal 299 similarly connected to the circuit cut-out switch 108 and a terminal 300 connected to a "plus" terminal 301 of the motor 252. To simplify future reference to electric circuits appearing at both top and bottom of Fig. 3, that portion of the wiring commonly interconnecting the "plus" pole of the battery 105 with parts "242—243—244—232a through c" will be referred to as a "gauge" electric circuit 302 and the remaining wiring of Fig. 3 will be referred to as a "selector valve drive" electric circuit 303.

Having fully described the construction and in the main the operation of the unitary selector valve drive 247, I now propose to disclose how the various parts thereof cooperate with the pressure responsive switch 9b, the control disk 137 and the electric circuit 303 embracing the ignition switch 106, battery 105, signal lamp 296, circuit cut-out switch 108, relay 104 and variable resistance 298, to effect automatic turning of the selector valve 4 from any "tank empty" condition to a "tank full" condition. In lieu of the ratchet wheel 42a, the hinged dog 112, the solenoid motor 102 and the motor control 103 of Fig. 1 and the ratchet wheel 42b, the hinged dog 229, the solenoid motor 102 and the circuit cut-out switch 131 of Fig. 2, I substitute the unitary selector valve drive 247 in the third embodiment of my invention. The Fig. 2 positionings of the fuel containers 1, 2 and 3, of the selector valve 4, of the control disk 37 and the pressure responsive switch 9b associated therewith, of the panel 25, and of the fluid associated parts to the right of the panel 25, remain unaltered in the third embodiment of my invention.

Let it be assumed, in Fig. 3, that switches 106 and 108 are in an "on" position and that the fuel pump 6 has not only exhausted the container 1, but that sufficient time has elapsed to effect simultaneous pressure drop in both the new pressure regulator 136 and the cavity 140 of the pressure responsive switch 9b, resulting in left hand movement of the switch carriage 150 into the "-P" position indicated. The aforesaid left hand carriage movement effects automatic "closing" of the pressure responsive switch 9b, resulting in electric current from the "plus" pole of the battery 105 being quadruply grounded, i. e. firstly at the signal lamp 296 (through parts "106—187—199—188—296"), secondly at the relay 104 (through parts "106—187—199—188—108—129"), thirdly at the motor 252 (through parts "106—187—199—188—108—298—252") and fourthly at the clutch solenoid 255 (through parts "106—187—199—188—108—290—292—294—255"). The aforesaid current flow results in lighting of the signal lamp 296, which in combination with the panel element 232a now gives double indication that the fuel container 1 is in "tank empty" condition; results in closing of the make-and-break portion of the relay 104 (the special significance of which is dealt with below); results in immediate rotation of the driving bevel gear 254 and therefore the disk 263 (momentarily); and results in immediate extension of solenoid plunger rod 269, causing simultaneous though opposite rotation of the combi-

nation clutch member-idler gear 266 and the driven gear 272 forming a fixed part of the extension shaft 37.

As the driven gear 272 commences its counter-clockwise rotation (see Fig. 3), the tripping cam 274a of the disk 273 forces the contactor arm cam 293 to the right, "breaking" the contact points 292 and 295 and positioning the leaf spring cam 291 in the path of an oncoming disk cam 264. Two results are obtained by the foregoing. Firstly (assuming, for the mere purpose of simplifying the illustration in point, momentary disconnection between the breaker 238 of the tank element 231a and the separate brush 268a of the three circuit interrupter 282), stoppage of current flow to the clutch solenoid 255 causes the solenoid plunger rod 269 to return to the positioning of Fig. 3, resulting in immediate rotational stoppage of the disk 273. Secondly, 15 positioning of the leaf spring cam 291 in the path of an oncoming disk cam 264 momentarily delays rotation of disk 263 in a clockwise direction until the spring 265 becomes sufficiently tensioned to cause one of the tripping cams 264 to bend 20 the leaf spring 290 to the left sufficiently to produce closing of the contact points 292 and 295. Since so long as the pressure responsive switch 9b remains closed, the motor 252 continues to turn; the tripping cam 274a of the disk 273 moves past the contactor arm cam 293 and the disk 273 continues a quarter turn until the oncoming tripping cam 274b contracts the contactor arm cam 293. In the last named positioning of the disk 273, the long end of the L-shaped 25 passageway 34 of the selector valve 4 is in registry with the inlet 29b operably connected to fuel container 2, and the fuel pump 6 commences to build up joint pressures in the pressure regulator valve 136 and the cavity 140 of the pressure 30 responsive switch 9b. As the tripping cam 274b of the disk 273 moves the contact arm cam 293 to the left, the tripping cam 138b of the control disk 137 moves into alignment with the cam 196 of the pressure responsive switch 9b. Tensioning 35 of the spring 265 is so calculated as to permit full right hand movement of the switch carriage 150 into the "+P" dotted position of Figs. 2 and 3. Since the cam 196 (switch 9b) and the tripping cam 138b (control disk 137) are in longitudinal alignment, the contactor arm element 186 is ultimately rotated in a counter-clockwise direction by full right hand movement of the switch carriage 150, causing "opening" of the pressure responsive switch and complete rotational 40 stoppage of the unitary selector valve drive 247.

Upon exhaustion of the fuel container 2, the switch carriage 150 again moves into the "closed" positioning of Fig. 3, and the above recited operation cycle of the unitary selector valve drive 247 is again repeated, this time in conjunction with tripping cam 274c of the disk 273 and the tripping cam 138c of the control disk 137. I have now progressed sufficiently with my explanation 45 of the operating characteristics of the unitary selector valve drive 247 to discuss in detail the special significance of the electric current from the "plus" pole of the battery 105 being grounded at the relay 104 (through parts "106—187—199—188—108—129") in conjunction with simultaneous closing of a breaker 238 of a tank element 231a through c and simultaneous electrical interconnection between a separate brush 268a through c, a commutator segment 285a through c and the three fingered single terminal brush 287.

For illustrative purposes, only, let it be assumed that instead of the "full" showing of Fig. 3, the fuel container 2 (due to air combat or mechanical defect) is in a "tank empty" condition. Then, when the tripping cam 274b of the disk 273 passes from its Fig. 3 positioning into registry with the contact arm cam 293, the commutator segment 285b will assume the present Fig. 3 positioning of the commutator segment 288a. Thereupon, current from the "plus" pole of the battery 105 will pass directly to the ground of the clutch solenoid 288 (through parts "242-243-244-232b-231b through closed 238-286b-285b-287-104-255"). This will result in "short circuiting" out the delaying effect of the hereinabove described initial opening, then closing of the contact points 292 and 295, resulting in elimination of selector valve "pause" when registering with an empty tank. Much time is thus saved in continuing rotation of the selector valve 4 until engagement with the fuel container 3 is effected.

In the description of the first embodiment of my invention, I made reference to certain existing limitations in present fuel delivery systems requiring pressure control at source of consumption. I have avoided these limitations, in the first three embodiments of my invention, by employing an engine fuel injector 10 having a pressure relief valve 228 (shown in Fig. 1) forming an integral part of the injector proper and by further providing piped connection between an outlet of the said relief valve and the inlet side of the fuel pump 6. Since unsupercharged engines, or engines in which the superchargers do not effect the carburetors, are normally equipped with fuel injectors or carburetors designed to operate under fixed fuel inlet pressures ranging from 3 to 15 pounds, for purely illustrative purposes I adjust the valve 228 such that it will by-pass to the inlet side of the fuel pump 6 all fluid pressures created in the pump outlet in excess of approximately three pounds per square inch. No such precautions, however, have been incorporated in the above referred to systems. These still persist in placing the fuel pressure regulator adjacent to the fuel pump, with inlet side connected to pump outlet and outlet side connected to pump inlet, such that any excess fluid pressure (over that required by a source of consumption such as a fuel injector or carburetor) will be immediately by-passed to the pump inlet. The operating limitations of an aircraft incorporating such a parts arrangement are briefly discussed in the second paragraph immediately below.

In Fig. 5, I disclose a modification in the fuel delivery portions of the second and third embodiments of my invention. Therein, I duplicate prior usage of the fuel strainer 5, the pump 6, the wobble pump 7, the switch pressure regulator 136 and the major portion of the engine fuel injector 10. From the last named, I omit the pressure relief valve 228 and the by-pass piping to the inlet of the fuel pump 6. To continue the function previously performed by the omitted relief valve 228 and by-pass piping, I add a fuel pressure regulator 304 with inlet connected to the outlet of the switch pressure regulator 136 by means of a pipe 305 and outlet connected to the inlet of the fuel pump 6 by means of a second pipe 306. In addition to the above, I add an aspirator 307 with a Venturi inlet 308 in continuation of the former pressure relief valve outlet of the engine fuel injector 10, with a main inlet 309 connected to the outlet of the switch pressure regulator 136 by means of a pipe 310 and a combined air-vapor

5 eliminator 8c and pressure responsive switch 9c connected with a main outlet 311 of the aspirator 307 by means of a pipe 312. Previous interconnections between the outlets of air-vapor eliminators 8a and 8b and the inlet of the fuel injector 10 are retained. A second outlet provided in the fuel pressure regulator 304 and an outlet provided in the (Fig. 2) line connecting the lower cavity 141 of the pressure responsive switch 9b with the induction system of a supercharged aircraft engine are piped to a two-way valve 313. In Fig. 5, the above second outlet is shown directly vented to the atmosphere.

10 Before proceeding with a detailed description of further new parts appearing in Fig. 5, or disclosing operation of my improved system as a whole, I wish to again return to the above discussed limitations in many existing fuel delivery systems. With the two exceptions of complete omission of the switch pressure regulator 136 (since same is peculiar solely to my invention) and substitution of a conventional "ball and spring" type pressure relief valve (or equivalent) in lieu of my new and novel type of fuel pressure regulator 304, let it be assumed that an aircraft 15 having its fuel tanks located well below the level of the fuel strainer 5 and an engine in which the supercharger does not affect the fuel injector 10 is equipped with the parts showing of Fig. 5. Let it be further assumed that the conventional 20 fuel pressure regulator mentioned above is set at approximately three pounds per square inch and that the aircraft takes off and maintains steady increase in altitude. Under such conditions, as the atmospheric pressure upon the top surface 25 of the fuel of the fuel tank then operably interconnected with the fuel pump 6 steadily diminishes, the magnitude of the suction necessary to raise the fuel into the rotor portion of the fuel pump 6 steadily increases. If climb is continued 30 to an altitude of between 23,000 to 28,000 feet, the "vacuum type" fuel pump 6 will have reached its maximum suction capacity and will have ceased further fuel delivery. However, long before any such altitude has been reached, steady climb will have increased the approximately one-half pound per square inch suction required for 35 ground transfer of fuel from "tank-to-pump" to a magnitude equal (though opposite in sign) 40 to the positive fuel pressure of three pounds per square inch maintained by the conventional fuel pressure regulator. Thereafter, no further increase in the magnitude of the suction required to transfer fuel from "tank-to-pump" can occur, 45 because of continuous pressure by-passing set up at this point by the conventional fuel pressure regulator. Obviously, further increase in altitude will terminate fuel flow in the pipe 310 through 50 "starving" of the rotor portion of the fuel pump 6. I have personally experienced just such an engine failure during flight test of a fuel system 55 of the character described.

60 In existing fuel systems incorporating the above limitations, there is a second operating factor which may cause engine failure. If, through human or mechanical defect, the receiving end of a selector valve passageway fails to correctly register with the delivery end of a selector valve inlet, thus introducing a restriction to fuel flow from tank outlet to pump inlet, an increase will occur in the magnitude of the suction necessary to raise fuel into the rotor portion 65 of the fuel pump 6. Such a restriction to fuel flow may readily assume proportions causing a duplication, at ground level or shortly after take-

off, of the hereinabove described continuous pressure by-passing at the fuel pump 6. I now propose to disclose how the modification in the fuel delivery portions of the second and third embodiments of my invention overcomes the limitations presented in the two paragraphs immediately above.

In Fig. 9, I provide a cup-shaped housing 314 with a horizontal inlet 315 and a vertical outlet 316 including a combination valve seat and venturi 317. The open end of a bellows 318 is adapted to be fixed to the top surface of the housing 314 by means of a cover plate 319 and gaskets 320. The bellows 318 is provided with a valve 321 fixed to and depending from the bottom of its closed end. The valve 321 is provided with a holdown spring 322a and compression adjustor 323. The latter includes an adjustor stem 324 with threaded lower end, a spring seat 325 secured to the lower end of the stem 324 and an adjustor knob 326 fixed to the unthreaded upper end of the stem 324. The cover plate 319 is provided with a packing gland 327 and packing gland collar 328 surrounding the adjustor stem 324. The cover plate 319 is provided with an outlet 329. Communication between the sealed interior of the bellows 318 and the outlet 329 is established by means of a passageway 330.

Let us now reapply the operating conditions presented in the third paragraph immediately above to the actual parts showing of Fig. 5 (note that the two-way valve 313 is vented to the atmosphere). With starting of the engine, if a fuel pressure of three pounds per square inch is to be maintained in the pipe 305, the adjustor 323 (of regulator 304) must be so set that upward pressure on the mean base area of the bellows 318 is exactly counteracted by the combined downward pressure of suction on the valve 321 and compression of the spring 322a. Upon accomplishment of the aforesaid "setting," let it be assumed that the aircraft takes off and maintains steady increase in altitude. As the one-half pound per square inch suction required for ground transfer of fuel from "tank-to-pump" steadily increases (with increasing altitude), the original sea-level atmospheric pressure within the interior of the bellows 318 undergoes like pressure decrease (due to its direct communication with the atmosphere) such that these two opposing pressures merely nullify one another (i. e. mere increase in altitude has no regulatory effect upon seating of the valve 321). On the other hand, any fuel pressure in excess of three pounds per square inch introduced into the housing 314 by the pipe 305 will cause immediate unseating of the valve 321 through upset of the combined downward pressure of the spring 322a and the initial or ground suction on the valve 321. I desire to note, in passing, that by usage of the venturi portion of the combined valve seat and venturi 317, I am able to use a smaller orifice to pass a given volume of fuel without unduly increasing the pressure or suction necessary to maintain such flow. The aforesaid usage of a venturi also tends to create a less turbulent flow and therefore decreases presence of vapor lock.

In the above paragraph, I described functioning of the fuel pressure regulator 304 with reference to an aircraft equipped with an unsupercharged engine or an engine in which the supercharger does not affect the fuel injector 10. Let us now consider an aircraft equipped with an engine in which the supercharger controls the air inlet pressure of engine fuel injector or car-

buretor. In such an installation, the fuel pressure of the engine injector or carburetor is referred to the aforesaid air inlet pressure at given altitude. Assuring a supercharger providing 5 sea-level condition and an initial (ground) setting of three pounds per square inch for the adjustor 322, the fuel pressure increase required in the pipes 305 and 310 of Fig. 5 (after aircraft take-off and steady increase in altitude) is equal 10 to the sum of said initial three pound pressure and the pressure difference between sea-level atmospheric pressure and the atmospheric pressure at any then given altitude. To obtain the foregoing fuel pressure increase, it is necessary only 15 that one adjust the two-way valve 313 (of Fig. 5) such that the interior of the bellows 318 is in constant communication with the induction system of the aforesaid supercharged engine. As the original ground atmospheric pressure surrounding the aircraft lessens in magnitude, with 20 continued increase in altitude, the aforesaid induction system increases in magnitude the initial (ground) sea-level atmospheric pressure within the interior of the bellows 318 (because 25 of its common interconnection with the aforesaid bellows interior). It thus obviously follows that for each pressure increment added to the interior of the bellows 318, a like pressure increment must be added to the exterior of the bellows 318 (by the fuel pump 6 through the interior of the pipe 305), if the whole is to remain in equilibrium.

In Fig. 10, I show structural modification of the fuel pressure regulator 304 of Figs. 5 and 9. 35 In lieu of the cup-shaped housing 314, I substitute horizontally disposed forward housing 332 and aft housing 333. I further substitute a hold-down spring 322b for the former spring 322a for reasons more fully discussed in detail hereinbelow. It will be noted that the combination valve seat and venturi 317 is now horizontally disposed in continuation of the horizontal inlet 315 and that the bellows 318 is turned end-for-end such that its interior is continuously in 40 communication with the vertical outlet 316 provided in the forward housing 332. The latter requires mounting of the valve 321 upon a stem 334 fixed to the closed end of the bellows 318 by means of a mounting disk 335. With addition 45 of gaskets 320, 320 and 329, the forward housing 332, the aft housing 333 and the unaltered cover plate 319 are assembled together as indicated in 50 Fig. 10.

Let us first consider utilization of the modified 55 fuel pressure regulator in connection with "unsupercharged engine condition." With starting of the engine, if the fuel pressure of three pounds per square inch is to be maintained in the pipe 305, the adjustor 323 (of Fig. 10) must be so set that rearward (right hand) pressure on the valve 321 is exactly counteracted by the combined forward (left hand) pressure of suction on the mean base area of the bellows 318 and compression of the spring 322b. Obviously, compression characteristics of the latter are far less in magnitude than those of the holdown spring 322a. Upon 60 accomplishment of the aforesaid "setting," let it be assumed that the aircraft takes off and maintains steady increase in altitude. As the one-half pound per square inch suction required for ground transfer of fuel from the "tank-to-pump" steadily increases (with increasing altitude), the original sea-level atmospheric pressure within the rear housing 333 undergoes like pressure decrease (due to its direct communication with the

atmosphere) such that these two opposing pressures (acting one within and one without the bellows 318) merely nullify one another (i. e. mere increase in altitude has no regulatory effect upon seating of the valve 321). On the other hand, any pressure in excess of three pounds per square inch within the pipe 305 will cause immediate unseating of the valve 321 through upset of the combined forward pressure of the spring 322b and the initial or ground suction upon the mean base of the bellows 318.

Utilization of the modified fuel pressure regulator should next be considered in connection with "increasing carburetor air inlet pressure supercharged engine condition." The two-way valve 313 (of Fig. 5) is first adjusted such that the interior of the forward housing 333 is in constant communication with the induction system of the aforesaid supercharged engine. Then, as the original ground atmospheric pressure surrounding the aircraft lessens in magnitude, with continued increase in altitude, the aforesaid induction system increases in magnitude the initial (ground) sea-level atmospheric pressure within the interior of the forward housing 333. It therefore obviously follows that with properly interportioning of "bellows" and "valve," for each pressure increment added to the exterior of the bellows 318 (through the rear housing 333), a like pressure increment must be added to the seated portion of the valve 321 (by the fuel pump 6 through the interior of the pipe 305) if the whole is to remain in equilibrium.

Before proceeding with the description of the modified combined air-vapor eliminator 8c and pressure responsive switch 9c, I desire to make brief comment with reference to the aspirator 307. Due to its close proximity to the engine into which it feeds fuel, the engine fuel injector 10 is subject to considerable heat transfer. This has a tendency to prematurely vaporize stagnant fuel therewithin. The latter I avoid by assuring constant fuel circulation from the Venturi outlet 308 of the aspirator 307 into the inlet 46 of the air-vapor eliminator 8c, from the outlet 47 (of the latter) into the inlet of the engine fuel injector 10, and from thence through body portion to outlet of the aforesaid injector 10.

Due to the more or less schematic nature of Fig. 11, I have reduced showing of details not involving modification, over the structure of Fig. 6, to a minimum. The essence of novelty in Fig. 11, over the showing of Fig. 6, concerns slidable mounting of a float guide 336 such that upon seating of the valve 64 in the valve seat 69, continuing upward fuel movement within the cup-shaped housing 44 will cause vertical bodily movement of said float guide 336 (against the compressive restraint of a spring 337) to a level resulting in opening of a fixed contact 338 connected to a binding post 339 and a movable contact 340 connected to a binding post 341. The contacts 338 and 340 perform the same functions as the contacts 89 and 90 of Fig. 6. Upon exhaustion of any fuel container operably connected to the air-vapor eliminator 8c (of Fig. 11), the reserve fuel contained in the cup-shaped housing 44 is pressure fed through the outlet 47 by the spring 337, since continuing operation of the fuel pump 6 prevents fuel escapage from the inlet 46 (of housing 44).

I provide the following new or substitute parts in Fig. 11. The slidable float guide 336 consists of an annular ring 342 with vent holes 343 and 344, of a lower housing 345 with vent holes 346

(depending from said ring) and of an upper housing 347 fixed to the top surface of the annular ring 342. The bottom of the lower housing 345 is cupped out to form a journal guide for the tube 57 (of the float 59). The valve seat 69 is fixed to an aperture provided in the top of the upper housing 347 such that it acts as a base guide for the spring 337. The outer diameter of the annular ring 342 is in turn guided by a cupped sleeve 348. The latter is provided with vent holes 349a and 349b, a turned over mounting flange 350 and a mounting gasket 351. Immediately upon the top of the mounting flange 350, I place a thin annular disk 352 to the lower inner surface of which I fix the upper end of a flexible liquid sealing element or bellows portion 353. The lower end of the bellows portion 353 is also fixed to the top surface of the annular ring 342. The utility of the latter bellows portion will be discussed in detail hereinbelow.

The cup-shaped housing 44 is provided with a cover plate-housing 354 (secured by conventional screw-lockwasher means). A vertical cavity 355, of the housing 354, is provided with a sleeve 356 adapted to act as a primary guide for the float guide 336. The top of the housing 354 includes a spring cavity 357; vent line passageways 72, 73 and 74; and a contactor pin hole 358. A contactor pin 359 (of insulating material) with major portion depending from the bottom surface of a contactor housing 360, is adapted to be vertically slidably guided by the hole 358 (in the housing 354). Upward movement of the pin 359 is required to "open circuit" the insulated movable contact 340 with respect to the grounded fixed contact 338. Obviously, the fixed contact 338 may be insulated from the housing 360, if desired. The contactor housing 360 can be fixed to a shelf 361 provided upon the top outer surface of the cover plate-housing 354 by any of several well known conventional means.

The combined air-vapor eliminator 8c and pressure responsive switch 9c operate as follows: Assuming initial "fuel-empty" condition, fuel from the fuel pump 6 first enters the inlet 46, spills over the top of the deflector 50, and then rises in the latter until it flows through vent holes 346, 343, 344, 349a and 349b to an upward level approximating the middle of the last named vent hole. So far, air originally occupying the empty air-vapor eliminator 8c has found ready escape through the open valve seat 69 and vent passageways 72, 73 and 74. Thereafter, further fuel flow divides itself in inner zone A and outer zone B flow. Due to air trap, the latter does not progress to the top of the cup-shaped housing 44. The former, however, ultimately completely fills the upper housing 347. When fuel in the inner zone A reaches a point slightly above the buoyancy level of the float 50, the valve 64 closes the valve seat 69. Thereafter, pressure from the fuel pump 6 must be relied upon, if further liquid rise is to be accomplished within zones A and B. Ingress of further fuel, under steadily increasing pump pressure, causes the spring 337 to steadily depress, permitting corresponding float guide 336 (and contents) upward movement until its uppermost surface effects vertical rise of the pin 359. So long as the fuel pump 6 continues normal functioning, the contacts 338 and 340 will remain in "open-circuit" condition and the engine fuel injector or carburetor connected with the outlet 47 (of the housing 44) will continue to receive fuel under a predetermined pressure.

In addition to the above, during the time interval between exhaustion of a fuel container, automatic turning of the selector valve 4 to an unexhausted fuel container, and passage of fuel from the new container outlet to the air-vapor eliminator inlet, the engine fuel injector or carburetor will continue to be fed reserve fuel under pressure from the cup-shaped housing 44 (of the eliminator 8c).

In the first three embodiments of my invention, I illustrate association of the pressure responsive switches 9a, 9b and 9c with the fuel delivery portion of my fuel system. I do not desire, however, to infer thereby that general application of my pressure responsive switch must be so limited. In Fig. 12, I show an embodiment of the aforesaid switch adapted for association with the source selector portion of the first embodiment of my invention. During operation of the switches 9a, 9b and 9c (shown in Figs. 6, 7 and 11), "open-circuit" condition thereof is automatically maintained so long as the fuel pump 6 is delivering fuel to an engine fuel injector inlet or a carburetor inlet under a predetermined (positive) pressure. In the pressure responsive switch 9d (shown in Fig. 12), "open-circuit" condition is automatically maintained so long as the fuel pump 6 is connected to and continuously removing fuel from an unexhausted fuel container under a predetermined (negative) pressure or suction. It is of course to be understood that the pressure responsive switch 9d may equally well be applied to a pipe through which fuel is being continuously gravity fed, as I employ conventional venturi means to effect pressure drop in the bellows element of my switch.

In Fig. 12, I place a venturi 362 adjacent to the fuel strainer 5. Obviously, any insertion between selector valve outlet and fuel pump inlet will serve equally well. The venturi 362 includes a main inlet 363 connected to the outlet of the selector valve 4, a main outlet 364 connected to the inlet of the fuel strainer 5, and a Venturi inlet 365 connected with the outlet of the pressure responsive switch 9d. The last named consists of a bellows element 366 supported by a cover plate 367 and a contactor element 368 fixed to the bottom of a cup-shaped housing 369 which last named housing is provided with a vent hole 370. The bellows element 366 comprises a bellows 371 with open end soldered or otherwise fixed to the cover plate 367, the closed end thereof being provided with a depending contactor pin 372 (of insulating material), and a compression spring 373. The upper end of the spring 373 is guided in a recess 374 provided in the cover plate 367, which also includes an outlet 375 connected to the Venturi inlet 365 by a short pipe 376. The contactor element 368 comprises a fixed contact 377 supported by a threaded post 378 (of insulation material) fixed to the cup-shaped housing 369 by means of a lock nut 379 and a movable contact 380 supported by a second threaded post 381 (of like material and fixity). The movable contact 380 includes a leaf spring 382 tensioned such that upward movement of the contactor pin 372 effects immediate separation between the movable contact 380 and the fixed contact 377 (i. e. produces "open-circuit" condition).

Operation of the pressure responsive switch 9d is as follows: During that period between any one fuel container exhaustion and renewed fuel flow from the next unexhausted fuel container, fuel momentarily disposed between selector valve

and fuel pump first ceases to flow and then upon renewed flow becomes such a mixture of air and fuel that passage of the aforesaid mixture through the venturi 362 greatly reduces "suction effect" upon the Venturi outlet 365. As long as mixed passage of air and fuel continues through the venturi 362, a "closed-circuit" condition prevails. However, with renewed fuel flow, increased pressure drop in the Venturi outlet 365

10 depresses the bellows 371, causing upward movement of the contactor pin 380 and thereby immediate "open-circuit" condition.

In Figs. 13 and 14, I disclose a very simple alteration in the three circuit interrupter 282 (of Figs. 3 and 4) whereby the unitary selector valve drive 247, or the altered interrupter in combination with the valve driving means shown in Figs. 1 and 2, may be applied to any aircraft having recesses provided in the bottoms 20 of its fuel containers 1, 2 and 3 into which the float portions of tank elements 231a, 231b and 231c may descend such that "down float" condition indicates "tank empty" condition. When combined with the pressure responsive switch 25 9d (of Fig. 12), the above may be equally well applied to either gravity or pressure fed fuel dispensing systems. If desired, the tank portions immediately above the aforesaid recesses may be hopper shaped. To save needless addition of 30 further figures, I describe operation of the above modification with reference to the parts showing of Figs. 3 and 4. Obviously, the altered interrupter may be equally well affixed to the extension shafts 37 of Figs. 1 and 2 (plus appropriate valve driving means interconnection). To further simplify my illustration, I reduce employment of parts to a minimum. I do not however desire, by so doing, to infer that the new three circuit interrupter 383 (shown in Figs. 13 40 and 14) shall be limited to interaction only with these parts, nor do I wish to be excluded from same such obvious simplifications in the present parts arrangement of the unitary selector valve drive 247 as omission of the clutch element 45 249 (through direct motor drive of the driven gear 272), etc.

In Figs. 13 and 14, it will be seen that I so laterally space the three commutator segments 384a, 384b and 384c that each can be respectively contacted only by separate brushes 286a, 286b and 286c. I further so stagger the circumferential arrangements of the commutator segments 384a, 384b and 384c that first "384a," then "384b," then "384c" bridges the gap between 55 the three finger single terminal brush 287 and the three separate brushes 286a, 286b and 286c. Referring specifically to Fig. 14, with the shaft 37 in such a position as to register the long end of the L-shaped passageway 34 (of valve 32) in 60 registry with the inlet 29a of the selector valve 4 (as shown in Fig. 2), I position the leading (left) edge of the commutator segment 384a angle a past the outer end of the contacting tip of the brush 287. The "gap" between this tip and the outer end of the contacting tip of the separate brush 286a is designated angle b . The degree value of either is a mere matter of design choice. Not so, however, is the angle c . Due to the 90 degree spacing between the inlets 29a 65 and 29b of the selector valve 4, the angle c must also equal 90 degrees. In summation, then, from leading edge to trailing edge the commutator segment 384a extends angle a_1 and from leading edge to the outer end of the contacting tip of the separate brush 286a it extends angle 70 75

e1. The leading edge of the next commutator segment 384b is then positioned angle e_2 in advance of the trailing edge of the commutator segment 384a. The leading edge of the last commutator segment 384c is thereafter positioned angle e_3 in advance of the trailing edge of the commutator segment 384b. From leading to trailing edges, all segments extend the same number of degrees. For convenience, these are designated angles d_1 , d_2 and d_3 , respectively.

Referring to Figs. 3 and 4, let it be assumed that the cylinder 284 (of insulating material) is equipped with the three (modified) commutator segments 384a, 384b and 384c, thus forming with the present three separate brushes 286a, 286b and 286c and the three fingered single terminal brush 287, my new three circuit interrupter 383. Let it be further assumed that the terminal of the brush 287 is directly connected to both the terminal 288 of the solenoid 255 and the terminal 299 of the variable resistance 298. Then, under the "tank empty" condition of the fuel container 1, electric current from the battery 105 will pass jointly to the solenoid 255 and the motor 252 (through parts "242-243-244-232a-231a-286a-384a-287-288," in the first instance and additional parts "299-298-300-301" in the second instance). The commutator segment 384a will thereupon execute a counter-clockwise movement just sufficiently in excess of 90 degrees to cause separation between the trailing edge of the commutator segment 384a and the separate brush 286a and will thereby effect stoppage of further current flow to the motor 252. The selector valve 4 will remain in communication with the fuel container 2 until the latter reaches "tank empty" condition. Thereafter, the above described cycle of operation of the commutator segment 384a is repeated with the commutator segment 384b, resulting in the selector valve 4 being brought into registration with the fuel container 3. As the last named registry reaches "tank empty" condition, the commutator segment 384c executes a counter-clockwise movement sufficient to bring about separation of the trailing edge thereof from the separate brush 286c and thereby registration of the pointer 43 (of the manual control handle 40) with the legend "off" provided at the bottom of the control panel 25. While I have so arranged the angular spacing between the leading edge of the commutator segment 384a and the trailing edge of the commutator segment 384c that the former falls short of closing the gap between the three fingered single terminal brush 287 and the separate brush 286a upon exhaustion of the final fuel container 3, it is of course to be understood that I can advance (i. e. extend) the leading edge of the commutator segment 384a or that I can collectively increase the lengths of the three commutator segments 384a, 384b and 384c (i. e. dispense with the legend "off") such that a continuous cycle of operation is provided for. Thus, if the selector valve 4 is initially registered with the fuel container 2 or 3, the above cycle of operation will continue after exhaustion of the fuel container 3.

Having thus described the various features of the invention, what I claim as new and desire to secure by Letters Patent is:

1. In a system for dispensing fuel to a source of consumption, a plurality of containers, a selector valve with a separate input connection to each of said containers, a venturi with main

inlet connected to the output of said selector valve, a fuel pump with input connected to the main outlet of said venturi and output connected to said source of consumption, switching means in communication with the suction outlet of said venturi closed by predetermined suction diminution in said suction outlet, and means operative upon successive switch closures for effecting appropriate movement of said selector valve.

2. In a system for dispensing fuel to a source of consumption, a plurality of containers, a selector valve with a separate input connection to each of said containers, valve turning means with independent manual element and motor element, a fuel pump with input connected to the output of said selector valve, an air-vapor eliminator with fuel inlet connected to pump output with fuel outlet connected to said source of consumption and with vapor outlet vented to a fuel container, switching means in pressure communication with said air-vapor eliminator closed by predetermined pressure drop therewithin, and means operative upon switch closure for effecting pre-timed control of the motor element of said valve turning means.

3. In a system for dispensing fuel to a source of consumption, a plurality of containers, a selector valve with a separate input connection to each of said containers, valve turning means with independent manual element and motor element having a control disk with disengaging cams bearing predetermined relationship to each selector valve input, a fuel pump with input connected to the output of said selector valve and output connected to said source of consumption, switching means in pressure communication with said fuel pump output and so constructed and arranged with respect to said control disk that each initial closing thereof by pressure drop in said fuel pump output is broken after predetermined valve turning by a control disk disengaging cam, and means operative upon switch closure for connecting the motor element of said valve turning means with a source of power.

4. In a system for dispensing fuel to a source of consumption, a plurality of containers, a selector valve with a separate input connection to each of said containers, valve turning means with independent manual element and motor element having a control disk with disengaging cams bearing predetermined relationship to each selector valve input, a fuel pump with input connected to the output of said selector valve, a switch pressure regulator with input connected to said fuel pump output and output connected to said source of consumption, switching means in pressure communication with a by-pass provided in said switch pressure regulator, said switching means being so constructed and arranged with respect to said control disk that each initial closing thereof by pressure drop in said fuel pump output is broken after predetermined valve turning by a control disk disengaging cam, and means operative upon switch closure for connecting the motor element of said valve turning means with a source of power.

5. In a system for dispensing fuel to a source of consumption, a plurality of containers, a selector valve with a separate input connection to each of said containers, valve turning means, a motor therefor, a control disk driven by said motor and provided with disengaging cams bearing predetermined relationship to each selector valve input, a fuel pump with input connected

to the output of said selector valve, a switch pressure regulator with input connected to said fuel pump outlet, an air-vapor eliminator with fuel inlet connected to switch pressure regulator output, with fuel outlet connected to said source of consumption and with vapor outlet vented to a fuel container, switching means in pressure communication with said fuel pump outlet and so constructed and arranged with respect to said control disk that each initial closing thereof by pressure drop in said fuel pump output is broken after predetermined valve turning by a control disk disengaging cam, and means operative upon switch closure for connecting the motor element of said valve turning means with a source of power.

6. In a system for dispensing fuel to a supercharged engine in which the supercharger does not control the air inlet pressure of its fuel injector, a plurality of containers, a selector valve with a separate input connection to each of said containers, valve turning means with independent manual element and motor element having a control disk with disengaging cams bearing predetermined relationship to each selector valve input, a fuel pump with input connected to the output of said selector valve, a switch pressure regulator with input connected to said fuel pump output and output connected to said source of consumption, constant fuel pressure control means bellows regulated with input connected to fuel pump output, with output connected to fuel pump input and with bellows outlet connected to the atmosphere, switching means in pressure communication with a by-pass provided in said switch pressure regulator, said switching means being so constructed and arranged with respect to said control disk that each initial closing thereof by pressure drop in said fuel pump output is broken after predetermined valve turning by a control disk disengaging cam, and means operative upon switch closure for connecting the motor element of said valve turning means with a source of power.

7. In a system for dispensing fuel to a source of consumption, a plurality of containers, a selector valve with prolonged turning shaft and a separate input connection to each of said containers, a control disk fixed normal to said turning shaft having disengaging cams like in number and angular spacing to said selector valve inputs, a fuel pump with input connected to the output of said selector valve and output connected to said source of consumption, switching means in pressure communication with said fuel pump output and so constructed and arranged with respect to said control disk that each initial closing thereof by pressure drop in said fuel pump output is broken after predetermined valve turning by a control disk disengaging cam, a unitary selector valve drive having a motor element, an electrically operated clutch element, and a shaft element forming an integral part of said turning shaft, and means operative upon switch closure for connecting said unitary drive elements including said electrically operated clutch element with a source of electric power.

8. A gravity feed fuel system for a source of consumption, a plurality of containers, a selector valve with a separate input connected to each of said containers, a venturi with main inlet connected to the output of said selector valve and main outlet connected to said source of consumption, switching means in communication with the suction outlet of said venturi and closed by

predetermined suction diminution therein, and means operative upon successive switch closures for effecting appropriate movement of said selector valve.

6. In the source selector portion of a fuel dispensing system, a plurality of containers, a selector valve with a separate input connected to each of said containers, a venturi with main inlet connected to the output of said selector valve, 10 switching means in communication with the suction outlet of said venturi and closed by predetermined suction diminution therein, and means operative upon successive switch closures for effecting appropriate movement of said selector valve.

10. In the source selector portion of a fuel dispensing system, a plurality of containers, a selector valve with a separate input connected to each of said containers, valve turning means with 20 independent manual element and motor element, a venturi with main inlet connected to the output of said selector valve, switching means in communication with the suction outlet of said venturi and closed by predetermined suction diminution therein, and means operative upon 25 switch closure for effecting pre-timed control of the motor element of said valve turning means.

11. In a fuel supply system for aircraft and the like having a plurality of fuel containers, a main fuel supply conduit, branch conduits connecting 30 the main conduit to the several containers, and automatic means adapted to be operated in response to the exhaustion of fuel from one container to connect another container to supply its fuel to the main conduit, said means including a rotary valve and means for imparting a step by step movement to the valve.

12. In a fuel supply system for aircraft and the like having a plurality of fuel containers, a main fuel supply conduit, branch conduits connecting 40 the main conduit to the several containers, a multi-way rotary valve controlling the fuel delivery from the containers, and means connected to impart a step by step rotary movement to said 45 valve automatically to connect said containers in succession to supply fuel to the main conduit as the fuel supply in the respective containers is exhausted.

13. In a fuel supply system for aircraft and the like having a plurality of fuel containers, a main fuel supply conduit, branch conduits connecting the main conduit to the several containers, a multi-way rotary valve controlling the fuel delivery from the containers, a motor controlled 50 mechanism connected to impart a step by step rotary movement to said valve, switch means controlling the mechanism and connected to be actuated in response to the exhaustion of the supply of fuel from any connected container to energize 55 the motor of the mechanism and thereby operate the valve to connect another container to supply its fuel to the main conduit.

14. In a fuel supply system for aircraft and the like having a plurality of fuel containers, a main fuel supply conduit, branch conduits connecting the main conduit to the several containers, a multi-way valve controlling the fuel delivery from the containers, a motor, ratchet means operated 60 by the motor and connected to actuate said valve, switch means controlling the motor and connected to be actuated in response to the exhaustion of the supply of fuel from any connected container to energize the motor and thereby actuate the 65 ratchet means for operating the valve to connect

another container to supply its fuel to the main conduit.

15. In a fuel supply system for aircraft and the like having a plurality of fuel containers, a main fuel supply conduit, branch conduits connecting the main conduit to the several containers, a multi-way rotary valve controlling the fuel delivery from the containers, a motor controlled mechanism coacting with and adapted to impart a step by step rotary movement to said valve, a solenoid connected to control the operation of the motor of the mechanism, switch means controlling the solenoid and connected to be actuated in response to the exhaustion of the supply of fuel from any connected container to operate the solenoid and thereby energize the motor to operate the valve for connecting another container to supply its fuel to the main conduit.

16. In a system for dispensing liquid to a source of consumption, a plurality of supply sources, liquid transfer means between supply and consumption having individual supply source selector means, control means for said source selector means, spring opposed, pressure operated bellows means, said control means being operated by said bellows means and said source selector means, said bellows means being operable upon a drop in liquid pressure through said liquid transfer means occasioned by the reception by the transfer means of air with the liquid to move said control means to a position for initiating operation of said source selector means, said bellows means, if the liquid pressure is restored, moving said control means to a position to be engaged by said source selector means and moved thereby to a position for stopping the operation of said source selector means, said bellows means, if low liquid pressure persists, leaving said control means in said position for initiating operation of said source selector means and thereby permitting the source selector means to continue operation to connect another source of supply with consumption.

17. In a system for dispensing liquid to a source of consumption, a plurality of containers, liquid transfer means between said containers and said source of consumption having individual container selector means, control means for said container selector means, loaded, pressure operated bellows means, said control means being operated by said bellows means on said container selector means, said bellows means being operable upon a drop in pressure through said transfer means occasioned by a change in the character of liquid flow therethrough to move said control means to a position for initiating operation of said container selector means, said bellows means, if pressure is restored, moving said control means to a position to be engaged by said container selector means and moved thereby to a position for stopping operation of the container selector means, said bellows means, if low pressure persists, leaving said control means in said position for initiating operation of said container selector means and thereby permitting the container selector means to continue operating to connect another container with said source of consumption.

18. In the fuel delivery portion of a system for dispensing fuel to a fuel injector and a su-

percharger of a supercharged engine in which the supercharger does not control the air inlet pressure of said fuel injector, a fuel pump having an output connected to said fuel injector, and a constant fuel pressure control bellows and casing having an input connected to the outlet of said fuel pump, and having an output connected to the inlet of said fuel pump, said bellows having an outlet on the side of the bellows opposite said input and said output and connected to said supercharger.

19. In the fuel delivery portion of a system for dispensing fuel to a fuel injector and a supercharger of a supercharged engine in which the supercharger does not control the air inlet pressure of said fuel injector, a fuel pump, an air-vapor eliminator with fuel inlet connected to the output of said fuel pump, and with fuel outlet connected to said fuel injector, and a constant fuel pressure controlled bellows and casing having an input connected to the output of said fuel pump and having an output connected to the input of said fuel pump, said bellows having an outlet on the side of the bellows opposite said input and said output and connected to said supercharger.

20. For an engine and a fuel injector therefor provided with a by-pass, a fuel delivery portion of the system for dispensing fuel to said fuel injector, a fuel pump, an aspirator having a main inlet connected to the output of said fuel pump and having a Venturi inlet connected to said by-pass provided in said fuel injector, an air-vapor eliminator with fuel inlet connected to the main outlet of said aspirator, with fuel outlet connected to said fuel injector, and provided with a vapor outlet, and a constant fuel pressure controlled bellows and casing having an input connected to the output of said fuel pump and having an output connected to the input of said fuel pump, said bellows having an outlet on the side of the bellows opposite said input and said output and connected to atmosphere.

21. In a fuel supply system for aircraft and the like having more than two fuel containers, a main fuel supply conduit, branch conduits connecting the main conduit to the several containers, and automatic means adapted to be operated in response to the exhaustion of fuel from one container to connect another container to supply its fuel to the main conduit, said automatic means including a rotating valve, electric motor means and a pressure responsive switch for controlling said electric motor means, said electric motor means upon operation imparting movement to said valve to move it from communication of said main conduit with the branch conduit extending to said one container to communication of said main conduit with another of said branch conduits extending to a second one of said containers, said electric motor means being thereafter operable to impart movement to said valve to move it from communication of said main conduit with said another branch conduit extending to said second container to communication of said main conduit with still another of said branch conduits extending to a third one of said containers.

DAVID SAMIRAN.
